ELASTIC BAND POWERED ROLLING TOY
 Norman A. Keck, 707 4th Ave., Joliet, Ill.
 Filed Sept. 19, 1962, Ser. No. 224,697
 7 Claims. (Cl. 46—206)

This application relates to a toy and more particularly to a toy of improved design of the type which can be rolled across a surface and will return again in a counter direction.

In some respects the toy of this invention is an improvement on the invention set forth in my Patent No. 2,814,160, dated November 26, 1957.

An object of the invention is to provide a toy having an effective and efficient drive roll for moving the toy in a back and forth direction.

Another object is to provide such a toy which can be easily constructed and with a drive roll which is in one piece and can be produced economically in quantity by molding or casting.

Another object is to provide such a toy having a drive roll which achieves good friction contact with a floor or other surface on which it may roll.

Yet another object is to provide such a toy having a drive roll which is easily attachable to elastic bands in the assembly of the device.

Other objects will be apparent as the specification proceeds.

The invention is illustrated in the accompanying drawings in which:

FIG. 1 is a plan view of the toy;

FIG. 2 is a side view;

FIG. 3 is a sectional view of one end portion, the section being taken along the line 3—3 of FIG. 4;

FIG. 4 is a sectional view of the end portion shown in FIG. 3, the section being taken along line 4—4 of FIG. 3;

FIG. 5 is a view similar to FIG. 3 but showing a modification of the toy; and

FIG. 6 is a view similar to FIGS. 3 and 5 but showing another modification of the toy.

As illustrated, the device includes a frame 10 in rectangular form, which may be made of wire or any other suitable material, having sides 11 and 12, and ends 13 and 14.

Within the frame are the drive rolls 15 and 16. As shown, these rolls are identical. They may be formed by casting or molding, using materials such as aluminum, steel, rubber, or plastics.

Referring particularly to roll 15 and FIGS. 1 to 4, the roll is generally cylindrical and spool-like in appearance. It has a central cylindrical body section 17 which is solid, and extending axially through this section is the fastening element 18. This element may be formed of wire, and as shown in FIG. 3, has the hook 19 extending from one end of the center section 17 and a hook 20 extending from the other end of this center section. Along its length is a crimp 21 which is an irregularity which prevents it from slipping endwise of the center section.

Extending from one end of the central section 17 is the frusto-conical section 22. The outside diameter of this section at the place it joins the central section is the same as that of the central section, and its diameter increases toward the outer end. At the outer end there is a cylindrical track 23 containing an annular channel 24. This channel receives the band 25 of friction material, such as a rubber band, which serves as a tread for the roll.

The frusto-conical section 22 is hollow, providing a cavity 26 extending axially from the end of section 22 back to the center section 17. The cavity also, is frusto-conical in form.

Another frusto-conical section 27 extends outwardly

2

from the other end of the central section 17. This section is exactly like the frusto-conical section 22 except that it faces in the opposite direction and extends from the other end of the center section.

5 An elastic band 28, which may be a simple rubber band, has its outer end connected with the right side member 12 of the frame and has its inner end connected with the hook 19.

The roll 16 is constructed and mounted similarly to 10 roll 15. Preferably, the axis of roll 16 is parallel with the axis of roll 15. In a sense the rolls 15 and 16 constitute respectively the front and rear wheels of a simulated vehicle. By using the pair of rolls the toy is stable in itself. However, only one such roll may be used and the toy stabilized by attachment to another rollable toy.

15 In operating this device, a person may grasp the frame and push the device along a surface a distance, or give it a push so that it moves a distance along the surface by momentum. In so moving, the rolls 15 and 16 rotate, causing the bands 28 and 29 to be twisted, thus bringing them under tension. At the end of such forward movement the tension which has been built up in the elastic bands moves to produce rotation of the rolls and so propels the device in a counter direction, until the bands 20 cause the device to move forwardly again, and so on, until the toy stops with the bands untwisted or substantially so.

25 It may be noted that the inner attachment of the elastic bands to the rolls is at points inward of the ends of the rolls and equidistant from the longitudinal center of the rolls. More specifically, the hooks 19 and 20 to which the inner ends of the elastic bands are attached, are each inward of the end of the roll a distance of about $\frac{1}{3}$ the length of the roll. For best results these points should be spaced apart a distance of from $\frac{1}{4}$ to $\frac{1}{2}$ the length of the roll. With its mountings so spaced, the roll may pass over bumps and irregularities in the surface at one or another end of the roll without disturbing the attitude of the frame, and yet there is sufficient stability that the 30 frame is always maintained against undue rolling or pitching.

35 Further, with the friction bands at the ends of the roll positive traction is provided, and with the bands mounted in the channels provided, there is assurance that the bands will not be displaced.

40 A modification of the device is shown in FIG. 5. This modification is the same as that shown in FIGS. 1 to 4, except that the fastening element 18a extends in a non axial direction through the central section 17a. In this modification the element 18a has its hook 19a near one side of the cylinder, and has its hook 20a near the other and opposite side of the cylinder.

45 In operating this modification of the toy, it will be apparent that rotation of the roll will produce a rolling effect on the frame, one side of the frame being urged upwardly while the other side is allowed to move downwardly, and this is followed by the opposite effect when the roll passes through 180°.

50 Another modification of the device is shown in FIG. 6. This modification is the same as that shown in FIGS. 1 to 4, except that the fastening element 18b extends through the center section 17b in a direction parallel with but spaced from the axis of the roll. In operating the modification of FIG. 6, it will be apparent that rotation of the roll will cause the frame to bob up and down.

55 In the principal embodiment and in each of the modifications illustrated the fastening element may be molded into the roll as it is formed, and the central crimped portion serves to keep the fastening element in place. Alternatively, the end of the central section can be tapped and the hooks screwed into the tapped hole, or the fastening 60 accomplished in any other way desired.

As before indicated, the rolls 15 and 16 may be molded of rubber, and when made of rubber it is not necessary to provide the channel 24, since the rubber itself provides a friction tread at the outer rim of the rolls.

Although in the embodiments illustrated the frame of the toy is shown as being formed of wire, it is a feature of the invention that the frame may be any kind of toy or body providing sides between which the rolls may be mounted as described.

While this invention has been illustrated and described in terms of preferred embodiments, those skilled in this art will appreciate that many changes may be made, and the invention may take many forms, all within the spirit of the invention.

I claim:

1. In a toy, the combination of a frame, a roll within said frame, said roll including a central cylindrical section and frusto conical end sections extending with increasing diameter from opposite ends of said cylindrical section, said end sections having cavities extending inwardly from their outer ends, an elastic band having its one end connected to said frame and having its other end extending into one of said cavities and connected to said roll at a point substantially inward of the outer end of one of said frusto conical sections, and a second elastic band having its one end connected to said frame and having its other end extending into the other of said cavities and connected to said roll at a point substantially inward of the outer end of the other of said frusto conical sections.

2. In a toy, the structure as set forth in claim 1 where-
in one of said elastic bands is connected to said roll at a point removed in one direction from the axis of the roll and the other of said elastic bands is connected to said roll at a point removed from the axis of the roll in a direction opposite said direction.

3. In a toy, the structure as set forth in claim 1 where-
in said elastic bands are connected to said roll at points equidistant from the longitudinal center of the roll.

4. In a toy, the structure as set forth in claim 1 but including a fastening element extending lengthwise through said central section and having a hook at each end which extends into said cavities so as to provide fastening means for said elastic bands.

5. In a toy, the structure as set forth in claim 4 where-
in said fastening element has an irregularity in its central portion to prevent its sliding endwise with respect to said roll.

6. In a toy, the combination of a frame, a roll within said frame, said roll including a solid central cylindrical section and frusto conical end sections extending with increasing diameter axially from each end of said central section, said end sections having central openings extending axially throughout their length, an elastic band having its one end connected to said frame and having its other end extending through one of said openings and connected with one end of said central section, and a second elastic band having its one end connected to said frame and having its other end extending into the other of said openings and connected to the other end of said central section.

7. In a toy, the structure as set forth in claim 6 where-
in each of said elastic bands is connected to said roll at a point removed in one direction from the axis of the roll.
